HANDKERCHIEF HOLDER

Robert M. Bryant, High Point, N.C.

Application March 4, 1959, Serial No. 54,828

Term of patent 14 years

(Cl. D17—3)

I claim:

The ornamental design for a handkerchief holder, substantially as shown.
